UNITED STATES PATENT OFFICE.

FREDERICK BENOIT, OF CHICAGO, ILLINOIS.

THILL-TUG.

SPECIFICATION forming part of Letters Patent No. 340,654, dated April 27, 1886.

Application filed February 23, 1884. Serial No. 121,677. (No model.)

To all whom it may concern:

Be it known that I, FREDERICK BENOIT, a citizen of the United States, residing in Chicago, in the county of Cook and State of Illinois, have invented a new and useful Improvement in Thill-Tugs, of which the following is a specification.

This invention relates to improvements in thill-tugs; and it consists in the novel features hereinafter set forth.

The accompanying drawings show at Figure 1 a perspective of my improved tug, and Fig. 2 a central vertical section thereof. Fig. 3 is a side view of the buckle whereby the ends of the tug are secured, and which carries the loop for the back-band depending from the saddle of the harness. Fig. 4 is a section of the same parts on the line 4-4 of Fig. 3, and Fig. 5 is the bottom or inside view thereof. Fig. 6 shows in section the metal piece supported in the tug and from which depends the girth, and in proximity to this piece is shown the leather cushion, which is held in it and upon which the thill rests. Fig. 7 is a central cross-section of the cushion, and Fig. 8 a bottom view of said metal piece. Fig. 9 is a section showing a modified construction of the metal piece.

In said drawings, A represents the strap forming the tug, and B the buckle by which it is supported from the saddle. One end of the strap A is passed over the tongue and tongue-bar of the buckle B, thence under a cross-bar, c, and secured upon a tongue or pin, c', upon said bar. This bar and pin form part of the buckle C, which embodies also the cross-bars c², c³, and c⁴ and the longitudinal connecting-bars c⁵. The body of the strap A, from its attachment to the buckle B, just described, passes under bar c² and over bar c³, and thence around, to form the loop of the tug, to the buckle B again, the end thereof being inserted over the tongue of buckle B under bar c⁴, upon pin c', and under bar c⁵. The longitudinal bars of the buckle C are provided upon the interior thereof and along their straight portions with clamping-ridges c⁶, serving as means to secure the loop C', through which the back-band is passed. In Fig. 4 these clamping-ridges are shown in the form in which they are cast, and, being of malleable metal, they are pressed up so as to take firm

hold of the edges of the loop C', and they may be provided with teeth, as shown, which will set into the material of the loop. It will be noticed that this buckle C is open upon the inside, and that the cross-bars are so located as to compel the strap A to project inwardly and beyond the metal parts of the buckle, save the cross-bar c, which is at the top of the tug, where contact with the thill is not likely to occur. By uniting the loop C' with this buckle, as specified, the amount of material required for said loop is lessened from the present mode of construction, it being now customary to continue the ends of the loop until they meet and can be stitched together. The loop is also secured to the buckle with all requisite firmness without any stitching whatever. In the bottom of the tug, I place a self-adjusting cushion device consisting of the metal frame D, made up of longitudinal bars d, cross-bars d', and depending loop d'', and a cushion secured in such metal frame. This cushion consists of a covering-piece, E, of leather, a retaining-piece, E', also of leather, and a filling-piece, E'', of some soft material. This covering and retaining-piece are stitched together centrally between the ends, as indicated by dotted lines in Fig. 6, and the upper surface of the retaining-piece is notched at e, to receive the cross-bars of the frame D.

As all the parts of the cushion are flexible, it is sprung into position in the frame D, with the retaining-piece under the cross-bars and the covering over them, as shown in Fig. 2, and the covering extends laterally, so as to lie over the longitudinal or side bars of the frame. From the under loop, d'', is suspended the girth F. The cross-bars d' ride upon the interior surface of the strap A, and thus support the frame and girth, while the cushion forms a support for the thill and prevents injury to it by contact with the frame. It will be noticed that this cushioned girth-supporting device is free to move in the tug, to accommodate differently-sized horses and differently-spaced thills, and that it automatically adjusts itself in this regard. The cushion is readily removed, and can be replaced whenever it becomes worn.

In Figs. 2 and 6, the girth-supporting-loop is so constructed as to bring the girth up into bearing contact with the strap A, so that the

cushion thus receives a support directly under its longitudinal center, and this may be desirable where the cross-bars d' are narrow, as in Fig. 6; but said cross-bars may be made broad, as in Fig. 9, in which case such central support will not be necessary, and the girth-loop may then be larger. If the girth be otherwise supported than from the frame D, then the cross-bar d' may be raised and serve simply the one purpose of supporting the strap and cushion.

The clamping ridge or jaw of the buckle C, whereby the loop C' is secured, may be upon the outside instead of the inside, and, indeed, such jaws may be used to embrace the loop-edge upon both the out and in side. Other material may be substituted for leather in the cushion, and instead of a cushion an unyielding substance may be employed at that point.

I claim—

1. The thill-tug consisting of the strap A, buckles B and C, frame D, and the cushion, all combined substantially as specified.
2. The combination, with the tug-strap, of the buckle C, constructed as shown, for holding the ends of the strap, substantially as specified.

3. The thill-tug provided with a movable cushion serving as a thill-support and held upon the interior surface of the tug by frame D, substantially as specified.

4. The frame D, having the cross-bars d' , in combination with the thill-support or cushion sprung into said frame, substantially as specified.

5. The combination, with the tug-strap, of the frame D, having the cross-bars d' and the thill-support or cushion secured in said frame, substantially as specified.

6. The cushion having the retaining-piece, in combination with the frame D, having cross-bars d' , substantially as specified.

7. The thill-support or cushion E and the tug-strap, in combination with the frame D, supported upon said strap and provided with a loop or cross-bar, d' , substantially as specified.

8. The combination, with the thill-tug and girth, of a frame, D, movable upon the interior surface of the tug and supporting the girth, substantially as specified.

FREDERICK BENOIT.
